CUTTER SUPPORTING MEANS FOR
WELL DRILLSFloyd L. Scott and Lewis E. Garfield, Houston,
Tex., assignors to Hughes Tool Company, Houston, Tex., a corporation of Texas

Application June 27, 1935, Serial No. 28,592

10 Claims. (Cl. 255—71)

Our invention relates to well drills to be employed in drilling deep wells for water, oil, gas and the like. It has particular reference to bits of this character having rolling cutters thereon.

5 It is an object of the invention to provide a construction of well drill in which the cutters and the shafts upon which they are mounted can be easily assembled in cutting position upon the head.

10 It is a further object to provide supporting means for the cutter shafts which are capable of adjustment at any time to accommodate wear.

15 It is another object of the invention to provide a well drill in which the cutters are mounted in open position where they can easily be flushed and cleared of mud or other material tending to adhere thereto.

20 We contemplate the construction of a well drill in which the cutters may easily rotate and be kept free of material so that they will not clog, said drill being of cheap and simple construction not liable to get out of order.

25 Referring to the drawing herewith:

Fig. 1 is a central longitudinal section through a well drill embodying our invention, said section being taken approximately on the line 1—1 of Fig. 2.

30 Fig. 2 is a similar longitudinal section taken at right angles to the one shown in Fig. 1 and on the line 2—2 of Fig. 1.

Fig. 3 is a transverse section on the line 3—3 of Fig. 1.

35 Fig. 4 is a perspective view on a somewhat reduced scale showing one of the supporting elements employed in the invention.

40 Our construction is generally in the form of what is known as the cross roller bit. We have a head 1 which is approximately cylindrical at its upper end and provided with an upwardly tapered shank 2 threaded to engage with the drill collar or coupling. Below the cylindrical upper end the body of the bit is cross-shaped in transverse section as shown in Fig. 3. The body 1 of the bit has oppositely extending ridges 3 thereon, each of which furnishes a mounting for a shaft supporting member 4.

45 The shaft supporting member 4 is mounted within a slot 5 cut longitudinally of the projecting ridge 3. The inner wall of the recess or slot 5 is of irregular contour as shown in Figs. 1 and 2 to accommodate the inner side of the supporting member 4.

50 The supporting member 4 is shown best in Fig. 4. It includes a narrow body member 7, which is provided between its ends with a transverse opening 8 to receive the pivot pin 9 upon which it is supported, said pin extending transversely across the slot 5 as shown in Fig. 3. The upper end of the supporting member is extended inwardly at an inclination as shown at 10, thus providing

an arm which is provided with a threaded opening therein to receive the set screw 11. Said screw is provided with a forward end 12 adapted to bear upon an inclined shoulder 13 on the inner wall of the slot 5.

5 The lower end of the supporting member 4 is provided with a head 14 which is wider than the body of the support and has upper shoulders 15 to engage below the lower end of the head shown in dotted lines at 16 in Figs. 1 and 2. The said head 14 projects below the body of the bit and has an opening 17 at its lower end to receive the end of the particular shaft which it supports.

10 The body of the bit 1 has centrally thereof a chamber 18 which forms a water course to conduct the flushing fluid downwardly through the body of the bit. At the lower end of this chamber is a wall 19 provided with inclined openings 20 to discharge the flushing fluid on the cutters of the bit. At each side of the lower end of the head about the water course are outer faces 21 which form the inner walls of the slots 5 and against which the supporting members 4 may contact, as will be later noted.

15 The cutters upon the bit are mounted upon two transverse shafts 22 and 23, said shafts being mounted at right angles to each other, the shaft 23 extending through an opening in the shaft 22. The shaft 23 is shown in Fig. 2 as extending diametrically across the lower end of the bit and having its reduced ends 24 supported in the lower ends of the supporting arms 4'. Upon this shaft are mounted a plurality of disc-shaped cutters 25 toothed to engage the formation and adapted to roll upon the shaft through roller bearing members 26. The cutters are separated from each other on the shaft by washers 27.

20 As will be noted from Fig. 2, the cutters are arranged to provide a mounting for three cutters at one side of the central portion of the bit and two cutters on the other side, thereby arranging said cutters so that each will cut its own track on the bottom of the hole.

25 On the shaft 22 are mounted two inclined side cutters 28 which are inclined inwardly at their upper ends, the lower ends projecting outwardly and beveled at 29 to cut the side wall of the hole and cut a clearance on the well bottom for the lower ends of the supports 4' for the cutter shaft 23. As will be noted the shaft 22 is inclined upwardly at each end so as to furnish a mounting for the cutters 28, allowing the said cutters to incline in the manner described. The ends 30 of the shaft 22 are supported in openings in the lower ends of the supporting arms 4. The side cutters 28 are provided with roller bearings 31 to facilitate their rolling action on the bottom of the hole.

30 It will be seen that the cutters in this type of drill are mounted on arms extending down below the main body of the drill. There are lateral

openings between adjacent arms which allow the flushing fluid to flow freely through and around the cutters upon the bottom of the hole.

When the cutters are assembled for mounting in the bit the two shafts 22 and 23 are assembled together in the manner shown and the cutters 25 and 28 are positioned thereon for operation and the arms 4 and 4' are then connected to the ends of the shafts and the assembly moved upwardly into position so that the pins 9 supporting the arms 4 and 4' are inserted and fixed in place. The set screws 11 are then tightened into position. It is obvious, as shown in the drawing, that one set screw can be tightened to throw the lower 15 end of the arm against the shoulder 21 and that the other arm can then be tightened by means of its set screw 11 to clamp the lower ends of the arms against shoulders shown at 32 and 32' on the shafts 22 and 23, respectively.

20 When the cutter shafts are thus clamped rigidly in place the completed drill bit assumes a rigid construction which is particularly strong. If, however, any wear occurs in the operation of the bit which tends to loosen the cutters upon the shaft any play may be taken up by further tightening of the set screw 11.

In a construction of this kind the parts which may be subject to wear are readily replaceable and if the lower ends of the arms 4 finally become worn enough to necessitate replacing, this may be readily done at a small expense. The head 1 of the drill may thus be used for long periods of time without necessity of removal. Cutters may be furnished for the drill in assembled position 30 upon arms 4 ready to be mounted upon the bit head without loss of time. The construction is therefore economical to use and easily mounted in position on the head.

It is also an advantage that the cutter shaft 40 supports 1 cannot easily become lost in the well through loosening or wear. The said supports fit closely within the slots 5, as will be seen in Fig. 3. In fact the inner and lateral faces contact closely with the walls of the slot. The cutters 45 could not be lost until the pivot pins 9 are removed, and loss of cutters is thus prevented.

What we claim as new is:

1. A well drill including a head, a diametrical cross shaft at the forward end thereof, a side 50 cutter shaft at right angles to said cross shaft and shaped with its ends inclined upwardly from the center, a row of disc shaped cutters on said cross shaft, a pair of side cutters on said side cutter shaft, and arms pivotally attached to said head to support the ends of said shafts.

2. A well drill including a head, a diametrical cross shaft at the forward end thereof, a side cutter shaft at right angles to said cross shaft and shaped with its ends inclined upwardly from 60 the center, a row of disc shaped cutters on said cross shaft, a pair of side cutters on said side cutter shaft, said head having spaced vertical grooves therein, arms pivotally supported in said grooves and having their lower ends extending below said head, said lower ends serving to support said shafts.

3. A well drill including a head, a diametrical cross shaft at the forward end thereof, a side cutter shaft at right angles to said cross shaft and shaped with its ends inclined upwardly from 70 the center, a row of disc shaped cutters on said cross shaft, a pair of side cutters on said side cutter shaft, pivot pins mounted transversely of 75 longitudinal grooves in said head, and arms piv-

oted between their ends on said pins, the lower ends of said arms projecting below said head, the said lower ends being formed with openings to receive the ends of said shafts and means to clamp the lower ends of said arms inwardly on said shafts.

4. A well drill including a head, opposed longitudinal ridges on said head, said ridges being formed with longitudinal grooves, arms supported pivotally in said grooves, the lower ends of said arms projecting below said head, a cutter shaft supported in said lower ends, cutters on said shaft, and means at the upper end of each of said arms to clamp said arms rigidly upon said shaft.

5. A well drill including a head, opposed longitudinal ridges on said head, said ridges being formed with longitudinal grooves, arms supported pivotally in said grooves, the lower ends of said arms projecting below said head, a cutter shaft supported in said lower ends, cutters on said shaft, and means at the upper end of each of said arms to clamp said arms rigidly upon said shaft, said means including set screws in said arms bearing against the inner portions of said grooves.

6. A well drill including a head, cross shaped 25 in transverse section, the four arms of the cross comprising longitudinal ridges on said head, said ridges being grooved to receive shaft supporting arms, arms in said grooves, pivot pins transversely 30 of said grooves supporting said arms, set screws at the upper ends of said arms to engage said head and move the upper ends of said arms outwardly, cutter shafts supported in the lower ends of said arms, said arms being tightened on said shafts when said set screws are screwed inwardly.

7. A well drill including a head, cross shaped in transverse section, the four arms of the cross comprising longitudinal ridges on said head, said ridges being grooved to receive shaft supporting arms, arms in said grooves, pivot pins transversely 40 of said grooves supporting said arms, set screws at the upper ends of said arms to engage said head and move the upper ends of said arms outwardly, cutter shafts supported in the lower ends of said arms, said arms being tightened on said shafts when said set screws are screwed inwardly, and shoulders at the lower ends of said grooved portion to limit the inward movement of said arms.

8. A well drill comprising a head, arms set in 50 grooves longitudinally of said head, means pivotally supporting said arms in said grooves, cutter supports on said arms of wider dimensions than said arms extending below said head, cutter shafts on said supports and cutters on said shafts.

9. A well drill comprising a head, arms set in 55 grooves longitudinally of said head, means pivotally supporting said arms in said grooves, cutter supports on said arms of wider dimensions than said arms extending below said head, cutter shafts on said supports, means to adjustably clamp the lower ends of said arms against said shafts, and cutters on said shafts.

10. A well drill comprising a head, arms set in 60 grooves longitudinally of said head, means pivotally supporting said arms in said grooves, cutter supports on said arms of wider dimensions than said arms extending below said head, cutter shafts on said supports, means to force the lower ends of said arms inwardly on said shafts, means on 65 said head to limit such inward movement, and cutters on said shafts.
